A. A. JOHNSON

TYPEWRITING MACHINE

Filed May 5, 1921

UNITED STATES PATENT OFFICE.

ARTHUR A. JOHNSON, OF WASHINGTON, DISTRICT OF COLUMBIA, ASSIGNOR TO UNDERWOOD TYPEWRITER COMPANY, OF NEW YORK, N. Y., A CORPORATION OF DELAWARE.

TYPEWRITING MACHINE.

Application filed May 5, 1921. Serial No. 436,944.

To all whom it may concern:

Be it known that I, ARTHUR A. JOHNSON, a citizen of the United States, residing in Washington, District of Columbia, have invented certain new and useful Improvements in Typewriting Machines, of which the following is a specification.

This invention relates to the art of typewriting and more particularly to improved means and methods for handling the webs or web and the manifolding material in continuous billing and like work.

At present there is on the market what is known as the "Underwood Fan-fold Biller", in which the platen of the machine is so mounted as to swing upwardly and forwardly to permit the course of the webs to be straightened sufficiently to enable or permit the carriage, on which the carbon sheets are mounted, to be moved rearwardly to move the carbon sheets to position to cooperate with the next "form". This movement of the carbon sheets and the platen takes place after a form has been completed. After the carbon sheets are retracted the platen is returned to normal position and the written form is severed from the unwritten form.

Now, according to this invention, fan-fold or other work sheets can be provided in "continuous" lengths and can be written upon and handled in an ordinary typewriting machine of commerce without necessitating any alterations in the existing structures and with a few additional parts, although the latter are not in all cases essential.

My new method consists in introducing to the platen of the machine the web or webs with the interleaved carbon sheets; then typewriting upon the web or webs; then removing entirely from the machine the work and the carbon sheets; then causing a bodily displacement of the carbon sheets relative to the work to move the carbon sheets and work into proper superposed positions with the form adjacent the written form; and then reinserting the work and carbon sheets and moving the same to writing position. Preferably, the carbon sheets are held against movement while the webs are advanced one "form" length.

According to this invention the carbon sheets are secured to a holder so that they are interleaved with the folds of the web, or

the separate sheets if such are used; and this carbon sheet holder is mounted upon the usual paper table or other suitable part of the typewriter carriage, the holder traveling with but being non-traveling with respect to the carriage. This is in contra-distinction to the usual arrangement in which the carbon holder is moved to travel on the typewriter carriage or its extension in a direction parallel with the length of the work sheet or sheets. Said usual carbon holder travels rearwardly when adjusting the carbons to the new "form" and forwardly, line-by-line as the writing operation progresses. In the operation of the present invention there is sufficient slack—or in other words, the carbon sheets are of sufficient length—to enable the work to extend in a loop when the work is introduced to the platen and brought to the writing line, that a form can be written to the last line without entirely straightening the loop and therefore without causing the carbon sheets to tend to move the carbon holder.

Other features and advantages will hereinafter appear.

In the accompanying drawings,

Figure 1 is a perspective view of the carriage portion of an Underwood typewriting machine, showing my invention as applied thereto.

Figure 2 is a side elevation of the same.

Figure 3 is a similar side elevation, showing the web removed from the platen and being moved forwardly to reposition the same with regard to the carbon-sheets.

As shown in the drawings, the rotary platen 10 of an Underwood typewriting machine is provided with an axle 11 mounted in the carriage frame 12. A paper table 13 guides the work between the platen 10 and 95 forwardly and rearwardly disposed feed-rolls 14 and 15, respectively, to the front of the platen to receive type impressions from the type 16a.

The feed-rolls 14 and 15 are supported by arms 16 pivoted upon a rod 17, and each provided with a depending arm 18, the arms 18 being oppositely disposed for receiving therebetween flat portions 19 of a rod 20 rotatably mounted in the carriage frame 12. The rod 20 may be controlled by suitable means, not shown, comprising an arm having a link connection with a feed-roll release

lever. Suitable springs, not shown, normally tend to hold the feed-rolls in contact with the platen or the work carried thereby, so that the latter feeds with the rotation of the platen. When the release key is depressed, the arms 18 are spread apart, causing the feed-rolls to be moved out of engagement with the platen or the work carried thereby. When this is done, the work can be freely introduced or removed from the platen without rotation of the platen.

It will be understood that the mechanism above described is that of the ordinary commercial Underwood standard typewriter.

According to the present invention, there is mounted upon the typewriter carriage, preferably in close proximity to the paper table 13, a carbon-holder 34, which comprises holders or arms 25, each secured at one end to the holder, so that its free end may extend into a fold of a fan-fold web 26 or between separate webs constituting the work-sheets. The arms 25 are adapted to hold sheets of manifolding material, such as carbon-sheets 27, the latter lying within the folds of the fan-fold web or between the plies of separate sheets forming the work-pieces, so that the type impressions are transferred to the under sheets of the work. The holders or arms 25, to which the carbon-sheets may be attached in any suitable manner, are supported in slotted blocks 21 at opposite ends of a plate 24, which curves downwardly at its rear edge to facilitate the feeding of the fan-fold web 26 there-over, and is supported by suitable means, such as a sheet-metal bracket 22. The arms 25 are recessed, as shown at the right in Figure 2, to obtain a better connection with the blocks 21, and said arms 25 are held in position in said blocks 21 by means of screws 23. As shown at the right of Figure 2, each arm has at one edge a tongue-and-groove connection with one of the blocks 21.

After the work is properly interleaved with the carbon-sheets 27 and their holders 25, the entire assemblage of work-sheets and carbon-sheets is introduced to the platen, preferably while the feed-rolls are released, and are thence guided to the line of writing by suitable guides 28, which guide the web beneath a knife 29, hereinafter referred to. The carbon-sheets are of sufficient length to permit the assemblage of web and carbon-sheets to extend to, and a distance beyond, the line of writing, substantially equal or slightly in excess of the longest "form" to be written.

After the assemblage of work has been brought to the line of writing, there is a slack between the platen and the carbon-holder, which will be gradually taken up as the writing progresses line by line (see Figure 1). Even after a form length has been fed, a slight slack remains to guard against

possible "over-run," and to facilitate the withdrawal of the web, as will presently be described.

After the form has been written upon, the web is, according to the present invention, withdrawn from the machine either by retrograde movement of the platen or by releasing the feed-rolls 14 and 15, by the operation of the release key. The web and carbons, being free from the platen, can then be relatively displaced longitudinally of the web. This is done, according to the preferred embodiment of this invention, by pulling the web forwardly while the carbon-sheets are held by the fixed holder 34. The extent of the forward movement of the web is equal to a "form" length, and this may be determined by special gages, if desired. But, in practice, I have found that the operative can accomplish the proper movement of the web without the aid of gages, for instance, by observing the position of the web relative to the carbon-sheets through the more or less transpicuous web.

The web having been advanced so that the carbon-sheets are no longer interleaved with the written portion of the web, the entire web, including the written portion, is reintroduced to the platen and advanced until the bottom of the written form is adjacent the knife 29. The feed-rolls are then caused to re-engage the web, and the written form is torn from the unwritten form along the edge of the knife 29.

The next form with which the carbon-sheets has been interleaved is then written upon, and the operations repeated.

It will be observed that there is provided a set of inking loops having the form of carbon-sheets 27 and co-operating with the types and platen, each loop comprising (1) a slack tab portion attached at its rear end to the stationary holder 25 and of sufficient length to reach when taut from said stationary holder to the printing line, and (2) a line-feeding portion extending in slack condition from said tab portion to the front of the platen, Figure 1, and of extended length permitting it to feed line by line up around the platen and receive many separated lines of type impressions thereon while the slack remains, and releasable means 14, 15 pressing upon the feeding side of the platen and co-operatively therewith line-feeding said slack inking loops, together with interleaved plies of slack work-web (usually divided into a succession of sections or forms) until the tab portions of said inking loops are nearly tautened by said line-feeding movements, while remaining attached to said stationary holder; said holder arranged at a distance from the platen affording room for the inking loops and interleaved work-plies to as-

sume a looped or slack condition when in position to receive the first line of typing upon a form, as at Figure 1.

Variations may be resorted to within the scope of the invention, and portions of the improvements may be used without others.

Having thus described my invention, I claim:

1. In a front-strike typewriting machine having a revoluble platen and a platen frame, the combination of a stationary holder mounted on the rear of the platen frame, a set of inking loops co-operating with the types and platen and each comprising (1) a slack tab portion attached at one end to said stationary holder and of sufficient length to reach when taut from said stationary holder to the printing line, and (2) a line-feeding portion extending in slack condition from said tab portion to the front of the platen and of extended length permitting it to feed line by line up around the platen and receive many separated lines of type impressions while the slack remains, and releasable means pressing upon the feeding side of the platen and co-operatively therewith line-feeding said slack inking loops, together with interleaved plies of slack work-web divided into a succession of forms, until the tab portions of said inking loops are nearly tautened by said line-feeding movements, while remaining attached to said stationary holder; said holder arranged at a distance from the platen affording room for the inking loops and interleaved work-plies to assume a looped or slack condition when in position to receive the first line of typing upon a form.

2. In a front-strike typewriting machine having a revoluble platen and a platen frame, the combination of a stationary holder mounted on the rear of the platen frame, a set of inking loops co-operating with the types and platen and each comprising (1) a slack tab portion attached at one end to said stationary holder and of sufficient length to reach when taut from said stationary holder to the printing line, and (2) a line-feeding portion extending in slack condition from said tab portion to the front of the platen and of extended length permitting it to feed line by line up around the platen and receive many separated lines of type impressions while the slack remains, releasable means pressing upon the feeding side of the platen and co-operatively therewith line-feeding said slack inking loops, together with interleaved plies of slack work-web divided into a succession of forms, until the tab portions of said inking loops are nearly tautened by said line-feeding movements, while remaining attached to said stationary holder; said holder arranged at a distance from the platen affording room for the inking loops and interleaved work-

plies to assume a looped or slack condition when in position to receive the first line of typing upon a form, and means adjacent the platen at its delivery side for severing the typed section of the work-plies after their re-insertion around the platen subsequently to the relative shifting between the work-plies and inking loops.

3. In a front-strike typewriting machine, in combination, a cylindrical platen, a frame in which said platen is mounted, said frame comprising a rear paper-table extending downwardly to the lower rear portion of said platen, and a device mounted at the upper edge of said paper-table to hold the rear ends of carbon-sheets interleaved between successive plies of a fan-fold web to be fed over the rear paper-table to the bottom of the platen, said device comprising a base-plate, the forward edge of which overlies the upper edge of the paper-table to feed the fan-fold web thereto, and the rear edge of which curves downwardly to facilitate the feeding of the fan-fold web thereover, a slotted block at each end of said plate, superposed carbon-carrying arms extending alternately from said blocks and supported in the slots therein which are arranged alternately at different heights, and screws, one associated with each block, for holding said carbon-carrying arms in position.

4. In a front-strike typewriting machine, in combination, a cylindrical platen, a frame in which said platen is mounted, said frame comprising a rear paper-table extending downwardly to the lower rear portion of said platen, and a device mounted at the upper edge of said paper-table to hold the rear ends of carbon-sheets interleaved between successive plies of a fan-fold web to be fed over the rear paper-table to the bottom of the platen, said device comprising a base-plate, the forward edge of which overlies the upper edge of the paper-table to feed the fan-fold web thereto, and the rear edge of which curves downwardly to facilitate the feeding of the fan-fold web thereover, a slotted block at each end of said plate, superposed carbon-carrying arms extending alternately from said blocks and supported in the slots therein which are arranged alternately at different heights, and screws, one associated with each block, for holding said carbon-carrying arms in position; said arms being recessed so as to fit over portions of said blocks and thereby assist in holding said arms in their proper positions.

5. In a front-strike typewriting machine, in combination, a cylindrical platen, a frame in which said platen is mounted, a device to hold stationary the rear ends of carbon-sheets interleaved between successive plies of a looped fan-fold web to be fed to the bottom of the platen, said device com-

prising a base-plate, a slotted block at each end of said plate, superposed carbon-carrying arms extending alternately from said blocks and supported in the slots therein which are arranged alternately at different heights, means for holding said carbon-carrying arms in position, and means for supporting said base-plate.

6. An attachment for use with a typewriting machine having a cylindrical platen and a frame therefor, comprising a rear paper-table to enable the machine to be used as a fan-fold machine, said attachment comprising a base-plate to overlie the upper edge of the rear paper-table, supports extending upwardly from opposite ends of said plate, superposed carbon-carrying arms extending alternately from said supports, and a bracket for supporting said base-plate on said platen-frame.

7. A typewriting machine of the character set forth, including a revoluble line-spacing platen, means arranged at the intake side of the platen capable of supporting superposed plies of web in slack condition, and means stationary at the line-feeding operation for detaining by their ends one or more carbon-sheets interleaved between the work-web plies and forming therewith a composite web, whereby the slack in the composite web is taken up by the line-feeding of the platen.

8. A typewriting machine of the character set forth, including a revoluble line-spacing platen, means arranged at the intake side of the platen capable of supporting superposed plies of web in slack condition, and means stationary at the line-feeding operation for detaining by their ends one or more carbon-sheets interleaved between the work-web plies and forming therewith a composite web, whereby the slack in the composite web is taken up by the line-feeding

ing of the platen, said supporting means including means to permit the web to be in a loop between the platen and carriage.

9. A typewriting machine of the character set forth, including a revoluble line-spacing platen, a carriage on which said platen is mounted, a frame extending backwardly from said typewriter carriage and connected thereto to travel therewith, said frame having at its rear a web-guide or support, and means stationary at the line-feeding operation for detaining by their ends one or more carbon-sheets interleaved between the work-web plies and forming therewith a composite web, whereby the slack in the composite web is taken up by the line-feeding of the platen, the loop or slack portion of the composite web extending forwardly between said rear web-guide and the platen.

10. A typewriting machine of the character set forth, including a revoluble line-spacing platen, a carriage on which said platen is mounted, a frame extending backwardly from said typewriter carriage and connected thereto to travel therewith, said frame having at its rear a web-guide or support, and means stationary at the line-feeding operation for detaining by their ends one or more carbon-sheets interleaved between the work-web plies and forming therewith a composite web, whereby the slack in the composite web is taken up by the line-feeding of the platen, the loop or slack portion of the composite web extending forwardly between said rear web-guide and the platen, said carriage having a paper-shelf in rear of the platen, and the loop of web occurring between said paper-shelf and said rear web-guide or support.

ARTHUR A. JOHNSON.
